Primary Examiner — Brett Miller*Assistant Examiner* — Mary Anne Arntzen(74) *Attorney, Agent, or Firm* — McCarter & English, LLP; Dave S. Christensen(57) **CLAIM**

The ornamental design for a mobile 3D coordinate measurement device, as shown and described.

DESCRIPTION

FIG. 1 is a front view of a mobile 3D coordinate measurement device, showing our new design;

FIG. 2 is a rear view thereof;

FIG. 3 is a right-side view thereof;

FIG. 4 is a left-side view thereof;

FIG. 5 is a top view thereof;

FIG. 6 is a bottom view thereof;

FIG. 7 is a first perspective view thereof; and,

FIG. 8 is a second perspective view thereof.

The broken lines depict portions of the article that form no part of the claimed design.

1 Claim, 8 Drawing Sheets(56)
